ROTARY ENGINES

James M. Dowell, 85 High St., Milford, Conn., and Robert F. Roy, West Haven, Conn. (2350 NE. 17th St., Pompano Beach, Fla.)

Filed Aug. 21, 1961, Ser. No. 132,753
12 Claims. (Cl. 123—16)

This invention relates generally to internal combustion engines, and particularly to those of the rotary type.

In the field of internal combustion engines, considerable effort and energy have gone into the development, design and manufacture of piston and cylinder type engines which are widely used to power automobiles. Although rotary engines were utilized to a limited degree as aircraft engines, particularly in the World War I era, they were of extremely crude form and never achieved any significant degree of perfection or acceptance.

In internal combustion engines, particularly of the type the application of which, such as in automobiles and aircraft, requires that they be portable, there are a number of desired features some of which conflict and among which are the following:

(1) Simplicity of design and construction. The desire here is to provide an engine having a minimum weight and size to horsepower ratio, which can be readily die-cast with a minimum number of dies for various horsepower ratings, and which may be easily mounted in any position for operation.

(2) Versatile and improved operation. Elements entering into this desired feature are to provide an engine: including a minimum number of moving parts and thereby reducing friction and wear; allowing for the use of a variety of gaseous or liquid fuels, such as gasoline, kerosene, natural gas (propane) or the equivalent; allowing for utilization of a plurality of the engines in series to increase horsepower without creating any difficult synchronizing problems; operating so as to require a simple, yet accurate, timing and control arrangement for both fuel supply and ignition which eliminates the need to advance or retard the spark during changes from low to high r.p.m.; operable at very high temperatures; scavenging 100 percent of the spent fuel; permitting air or liquid cooling; including a built-in supercharger; and which may be started by self-generated compressed air and eliminates any possibility of kick-back in starting.

It is an object of the invention to provide an improved rotary engine which includes all of the desired features set forth in the preceding paragraph.

Other objects and further details of that which we believe to be novel and our invention will be clear from the following description and claims taken with the accompanying drawings, wherein:

FIG. 1 is a perspective view of one form of the invention with the end cap removed and inverted to show its inner side for the sake of clarity;

FIG. 2 is an end elevational view thereof with the end cap removed;

FIG. 3 is a sectional view taken substantially on line 3—3 of FIG. 2 with some portions broken away;

FIG. 4 is a sectional view taken substantially on line 4—4 of FIG. 3 with a portion broken away for clarity;

FIG. 5 is a perspective view of the engine fly wheel showing the rope starter means;

FIG. 6 is a perspective view of the engine housing per se with portions broken away for the sake of clarity;

FIG. 7 is a perspective view of a subassembly of elements including the take-off shaft, the pair of driving vanes, the ring means and the means for supporting and sealing the vanes in the ring means with some portions broken away and others displaced for the sake of clarity;

FIG. 8 is a sectional view taken substantially on line 8—8 of FIG. 7;

2

FIG. 9 is a perspective view of one of the elements of the FIG. 7 subassembly, namely, a ring means section;

FIG. 10 is an elevational view of one of the slippers which form the driving vanes supporting said sealing means;

FIG. 11 is an exploded view of the pair of driving vanes and the take-off shaft;

FIG. 12 is an enlarged somewhat schematic view taken substantially on line 12—12 of FIG. 3 and showing the driving vanes solid, dotted and dot-dashed in three representative positions they assume during operation;

FIGS. 13 and 14 are schematic views which should facilitate an understanding of the operation of this form of the invention;

FIG. 15 is an end elevational view of another form of the invention;

FIG. 16 is a perspective view of a subassembly thereof;

FIG. 17 is a sectional view taken substantially on line 17—17 of FIG. 15, and

FIG. 18 is a sectional view taken substantially on line 18—18 of FIG. 17.

With reference to the drawings, in FIGS. 1—14 we have illustrated one form of our invention which is particularly useful for power applications under ten horsepower though not necessarily limited thereto. This form of the invention comprises a main housing which may be cast of a light-weight metal and conveniently made in two sections, a main section 10 and detachable end cap 12. The main section includes supporting means for mounting the engine in any desired position which, as illustrated, takes the form of a plurality of legs 14 and feet 16. The main section 10 includes a cylindrical side wall 18 and a diametral end wall 20 having a flat circular inner surface 22. The side wall 18 and end wall 20 cooperate to define a solid cylindrical space in the housing section 10. The end cap 12 is detachably connected to the main section 10 in any convenient manner, as by a plurality of threaded bolts 24 that are rigidly secured at one end of the main section 10 and which are arranged to be received in the openings 26 formed in the end cap 12 and have nuts 28 secured thereto. The inner surface 30 of the end cap 12 is circular and substantially flat and completes a solid cylindrical compartment C when the end cap is secured to the main section of the housing.

Centrally of the end wall 20 and coaxial with the compartment C there is formed a circular bore 32 into which is rigidly mounted in any convenient manner a radial bearing, such as a sleeve 34 (see FIG. 6). In the end cap 12 there is formed a centrally disposed bore 36 which rigidly supports a radial bearing, such as sleeve 38. The bearing sleeves are aligned and rotatably support a power take-off shaft 40 that extends completely through the housing (see FIG. 3).

In the surface 22 of the end wall 20 there is formed a circular groove 42 which is disposed eccentrically relative to the end wall and the bore 32 formed therein. In the inner surface 30 of the end cap 12 there is formed a similarly eccentrically disposed groove 44 which is arranged to be aligned with the groove 42 when the end cap is attached to the main housing section. It will be particularly noted in FIG. 6 that one point on the groove 42 (the lowermost one) is common with one point on the inner surface 70 of the side wall 18 of the main housing section which point falls on an axial line x. The aligned grooves 42 and 44 are arranged to receive and rotatably support a ring means generally designated by reference numeral 46 which subdivides the compartment C into two chambers, one chamber designated as a compression chamber which is formed within the ring means 46 between the surfaces 22 and 30, being circular in cross section and identified as CP in the drawings, and the other chamber designated as the combustion cham-

ber which is formed between the radially outer side of the ring means 46 and the radially inner side of the side wall 18 of the main housing section between the surfaces 22 and 30, being generally crescent-shaped in cross section and identified as CB in the drawings (see FIGS. 12-14). When the ring means 46 is fully assembled in the housing, it is mounted for substantially frictionless rotation therein and it cooperates with the housing, which is stationary, to form the referred-to chambers in a manner which seals them so as to be substantially airtight. To effect the frictionless mounting of the ring means, antifriction thrust bearings are mounted in the grooves 42 and 44, as ring sets of ball bearings 48 and 50, respectively, and have edgewise bearing contact with the respective opposite ends of the ring means.

Mounted on the shaft 40 is a pair of driving vanes 52 and 54, which preferably are made of hard steel, each vane including a main flat driving portion that is radially disposed in compartment C when the vanes are operatively mounted and a tubular mounting hub, as can most clearly be seen in FIG. 11. Vane 52 is directly drivingly connected to shaft 40, and therefore, includes an axial keyway 56 in the inner surface of its hub 58 which is arranged to receive a key 60 that is mountable in an axial keyway groove 62 formed in the shaft 40 to directly connect the vane 52 to the shaft 40 (see FIG. 3). The vane 54 is mounted on the shaft 40 so as to float thereon, and therefore, it includes a plain tubular mounting hub 64 that is freely rotatably mounted on said shaft. The vanes 52 and 54, when operatively mounted, extend radially through slots formed in the ring means 46, in a particular manner to be subsequently described in greater detail, and have their axially extending, free radially outer edges 66 and 68, respectively, in close sliding clearance fit with the inner surface 70 of the housing side wall 18. The structural arrangement of the shaft 40, vanes 52 and 54, and ring means 46 is such that they are capable of rotating jointly within the compartment C in the housing. During such movement, the edges 66 and 68 of the vanes have a close wiping fit with the inner housing wall 70 and the radially extending, parallel, side edges 72 and 74 of the vanes 52 and 54, respectively, have close wiping contact with the flat, parallel, end wall surfaces 22 and 30.

If it is desired to enhance the sealing and bearing relationship between the vanes and housing surfaces with which they have close wiping contact and reduce the wear of the vanes, the edges 66, 68, 72 and 74 of the vanes may be provided with elongated grooves, generally semi-circular in cross section, and elongated sealing members made of a good bearing and sealing material may be disposed in the grooves by having complementarily formed portions seated in the grooves and portions protruding beyond the edges of the vanes into good sealing contact with said housing surfaces. The arrangement is such that on rotation of the driving vanes, ring means and take-off shaft, the vanes rotate relative to the compartment C, but due to the eccentric relative disposition of the shaft and ring means, the vanes move radially in the slots in the ring means through which they extend and oscillate relative to the ring means, hence these elements though rotating jointly do not rotate uniformly. The vanes are mounted in the ring means so as to have bearing and sealing engagement with the portions of the ring means which define these slots; therefore, the compression chamber and combustion chamber are isolated by the ring means.

The detailed construction of the ring means and driving vanes subassembly and their cooperative relationship will now be described. With particular reference to FIG. 7, it will be observed that the ring means 46 comprises a pair of substantially semicylindrical sections 76 which are preferably made of a mild steel, a pair of detachable end rings 78 which preferably are made of bronze, and a pair of bearing and sealing means for the vanes 52 and

54 which are diametrically disposed and supported by the sections 76 and rings 78 when the ring means is fully assembled. Each bearing and sealing means comprises a pair of slippers 80 which may be made of a good bearing and sealing material, such as bronze, and cooperate when assembled in the ring means to form an elongated rectangular slot 82 of a shape to snugly receive a driving vane to support and seal it. The slippers are elongated, being longer than the axial length of sections 76, generally semicylindrical throughout the outer surface of their main axial central portions 84 and have tapered ends 86. When two slippers are operatively associated, their ends 86 cooperate to form conical mounting stubs for the assembled slippers which are receivable in complementarily shaped sockets 88 formed in the end rings 78, two of such sockets being formed and diametrically spaced in each ring 78. The axial length of the slippers is sufficient so that when they are operatively mounted relative to the sections 76, the mounting stubs formed by the tapered ends 86 extend axially beyond opposite ends of the sections 76 where they are disposed to be positioned in end ring sockets 88, when the ring means is fully assembled. At this time, the semicylindrical outer surfaces 84 of the slippers are positioned in axially extending arcuate grooves 90 formed on opposing free axial edges of the sections 76. On its inner side, each of the slippers 80 includes a cut-away notch 92 which oppose each other and cooperate when the slippers are assembled to form a slot 82 for a driving vane, two such slots being located at diametrically oppositely spaced locations on the completed ring means.

In order to physically assemble the ring means-take-off shaft-driving vanes subassembly, one exemplary procedure is to dispose one of the end rings 78 about the take-off shaft 40; mount the driving vanes 52 and 54 operatively on the shaft 40, i.e. vane 52 is keyed to the shaft and vane 54 is slid thereon, the hubs complementing each other axially to form a continuous tubular hub; dispose a pair of slippers operatively about each vane, i.e. they are placed 40 on opposite sides of the vanes to form the slot 82 about the vane; dispose the two sections 76 in position to form a cylinder with the grooves 90 in their opposing free axial edges disposed to contact and support a pair of assembled slippers 80, move the end rings 78 into juxtaposition with the axial ends of the sections 76 and slippers 80 disposed relative thereto so that the projecting conical mounting stubs of the slippers are received in the sockets 88 in the end rings and to secure the end rings to the sections 76, as by inserting securing screws 94 through appropriate openings 96 formed in the end rings and anchoring them in appropriate threaded openings 98 formed in the end edges of the sections 76. Other ways of assembling this subassembly may be employed, the foregoing one being merely exemplary.

The take-off shaft, driving vanes, ring means subassembly may be so assembled and then mounted as a unit in the engine housing by removing the end cap 12 and moving the subassembly axially into compartment C of the main housing section 10 while inserting one end of the shaft 40 through the bearing 34 and disposing one end of ring means 46 in groove 42. Thereafter, the end cap 12 may be mounted on the shaft 40 by having its bearing 38 slid thereon, by positioning the end cap so that its groove 44 slides over the other end of the ring means 46, and by securing the end cap to the main housing section. When fully assembled, an axial linear portion of the outer surface of the ring means has line sealing contact with an axially extending linear portion of the inner surface 70 of the housing, which line is designated arbitrarily and schematically by reference character x in FIGS. 2, 3 and 6. When these parts are so assembled, the shaft 40 is supported for rotation by the bearing sleeves 34 and 38, the ring means 46 is rotatably mounted with its end rings 78 disposed in grooves 42 and 44 in edgewise thrust bearing contact with bearings 43 and 50, and the driving vanes 52

and 54 rotate with the shaft 40. Rotation of the shaft 40 is accompanied by joint though not uniform rotation of the vanes 52 and 54 and the ring means 46. In operation of the engine, as will hereinafter be explained more fully, the driving vanes are forced to rotate by reacting to the force of exploding fuel, and they cause the shaft and ring means to rotate, the power being available for take-off at the ends of the shaft that are disposed on the exterior of the engine housing.

The engine housing is formed to include, support or accommodate the remainder of the engine elements. With particular reference to FIG. 6, it will be observed that the main housing section 10 has a pair of openings 100, 102 formed in and through the end wall 20 in position to fall within the groove 42, and therefore, to communicate with the compression chamber CP on the interior of the ring means 46 when the latter is assembled in the housing. Opening 100 is a fuel inlet valve and communicates through appropriate fittings and tubing 104 with a carburetor 106 which may be of any known convenient type and is disposed on the exterior of the housing. Opening 102 is a compressed fuel outlet valve and communicates through appropriate tubing 108 with a fuel control valve assembly 110 which may be conveniently formed in a fitting that is mounted detachably to the main housing section 10 at a point thereon wherein it communicates through a perforated fire screen 112 with the combustion chamber CB on the interior of the main housing section in an area immediately adjacent to one side of the line x (see FIGS. 2 and 6).

Adjacent to the valve assembly 110 there is disposed a spark plug 114, which may be conveniently incorporated into the referred-to valve fitting, and the electrodes of which are disposed adjacent to the surface 70, the spark plug being disposed in an opening in the main housing section that opens to the combustion chamber CB. Spark plug 114 forms part of an ignition system that may conveniently include an electrical cable carrying conduit 116, an ignition coil 118, a battery (not shown) and a control switch 120 (see FIG. 4). These ignition system elements may be of any known convenient type and operate to cause the spark plug to spark whenever the switch is actuated. The switch 120 is actuated by a cam 122 that is keyed to the shaft 40 by a key 124 on the exterior of the housing and which includes a pair of projecting cam ears 126 which are diametrically spaced and which cooperate with a cam following tripping lever 128 which forms part of the switch 120 to actuate the switch twice each rotation of the cam, hence cause the spark plug to spark twice a cycle.

Cam 122 also actuates a cam-following roller 130 that is rotatably supported by an elongated push rod 132 at one end of the latter. The push rod is mounted for reciprocable movement in a pair of apertured bearing blocks 134 formed on the end wall 20 and is operatively associated at its other end 136 with one end 138 of rocker arm 140 which is pivotally mounted by its hub 142 on a bearing pivot pin 144 that is rigidly supported on one of the feet 14 (see FIG. 1). The other end 146 of the rocker arm is operatively associated with the actuating end 148 of valve stem 150 which forms a part of the valve assembly 110 and which supports a valve body 152 internally of the valve assembly that is normally biased by compression spring 154, operating through its end retainer 155 and the valve stem, to close internal valve opening 156 but which is actuated twice a cycle by the rocker arm 140 to move to its dotted position shown in FIG. 2 to open the valve opening 156 and thereby permit the compressed fuel outlet 102 in the housing end wall 20, hence a portion of the compression chamber CP, to communicate through the tubing 108, the open valve opening 156 and fire screen 112 with the interior of the combustion chamber CB.

On the exterior of the engine housing, the take-off shaft 40 has rigidly connected to it, adjacent the cam 122, as by the key 124, a flywheel 158, which may be of any

known convenient type. One side of the mounting hub of the flywheel may be formed so as to permit starting of the engine by cranking it with a rope. This rope cranking formation may comprise an annular groove 160 which is formed in part by a radially outwardly extending flange 162, and one or more notches 164 formed in the periphery of flange 162 to allow the operative disposition of a rope knot in a notch prior to winding the rope in the groove 160 to permit engine starting by cranking with the rope in the usual manner. The flywheel performs the usual flywheel function of imparting smooth rotation to the take-off shaft.

With reference to FIG. 6, it will be observed that throughout one-quarter of the side wall 18 of the main housing section, adjacent to the line x, there are formed a plurality of elongated, parallel, circumferentially extending slots 166, which function as engine exhaust vents, as will hereinafter become apparent. The sealing contact of the cooperating linear portions of the ring means and housing at x, however, maintain the air-tightness of the combustion chamber CB between line x and a vane disposed in the unslotted portion of the side wall 18. If it is desired to enhance the seal between the ring means and housing at x by rendering it a surface-to-surface seal rather than just a linear one, the adjacent portions of the housing at x may be transversely arcuately recessed slightly so as to have a curvature equal to that of the outer circumference of the ring means, and the latter may be lowered slightly relative to the housing, as viewed in FIGS. 2 and 6, so as to extend into the recess into surface sealing contact with the recessed portion of the housing by reducing the outer diameter of the vane hubs 58 and 64, and lowering the grooves 42 and 44.

The foregoing comprises a detailed explanation of the construction of this form of the invention, insofar as detail is deemed necessary. The operation of the device will now be set forth. Reference to FIGS. 2, 12, 13 and 14, it is believed, will facilitate an understanding of the operation of the device. In these views, the driving vanes, ring means and take-off shaft rotate in a clockwise direction, as indicated by the arrows in FIG. 12.

For purpose of explanation we will start with the driving vanes disposed substantially in vertical alignment, as shown in FIG. 2 in solid lines, and in FIG. 12 in dot-dash lines. It will be observed that the compartment C is generally divided into compression chamber CP and combustion chamber CB, as previously described, by ring means 46, and that the compression chamber CP is further subdivided by the vanes into two sub-chambers, one to the right and one to the left of the vane 54, as shown in FIG. 2. (In other phases of a rotational cycle, the vanes are differently disposed, and subdivide the compression chamber into three sub-chambers.) With the vanes disposed vertically, to start a cycle of operation, the engine is cranked, as by turning the flywheel, by utilizing the rope starter, in a direction to cause ring means 46, shaft 40 and vanes 52 and 54 to rotate clockwise in the chamber C. This causes the vanes to move out of vertical alignment due to the mechanical movement caused by the eccentric mounting of the vanes and ring means axes. A charge of gaseous fuel will be induced by suction from the carburetor through the tubing 104 and opening 100 into a temporary subchamber S' in compression chamber CP being formed within the ring means 46 by and behind the upper driving vane which has moved from its vertical position I in FIG. 12 over fuel inlet opening 100, to its position II. For simplicity we will follow this vane and a single charge of fuel throughout this explanation. The incoming charge of fuel is designated by schematic arrows a in sub-chamber S' in FIG. 13 at this point in the cycle. Continued clockwise rotation of this vane to its dotted III position in FIG. 12 has the effect of increasing the size of the sub-chamber S' within the ring means and behind this vane, to admit more fuel, the fuel charge now designated a' in FIG. 14.

Continued rotation of the vanes causes them to reach a place (half cycle) wherein they are again vertically aligned, but inverted, i.e. the vane which originally was the upper one in the position shown in FIG. 12 at the start of the cycle is now the lower vane in position IV, the vane we are following throughout this explanation. At this time, there are again just two sub-chambers, and the right hand one in FIG. 12 is filled with the fuel charge occupying about half the compression chamber. Continued rotation causes this vane to move to the FIG. 12 position V and the other vane to sweep past fuel inlet opening 100 to induce a second charge of fuel behind it which we will disregard during this explanation, but which follows the fuel charge we are considering in sequence. At this time, the first fuel charge is being carried between the vanes and is designated *a'* in FIG. 13. Continued rotation causes this vane to reach FIG. 12 position VI, at which point it is about to pass over fuel outlet 102 to allow the first fuel charge, now designated *a''* in FIG. 14, to pass through opening 102 and tubing 103 to the valve assembly 110. Continued rotation causes the vanes to complete one complete cycle and reach their original, vertically aligned, FIG. 12 position, but the first complete fuel charge is now disposed in the left-hand sub-chamber and the second fuel charge is disposed in the right-hand sub-chamber. Continued rotation causes the first fuel charge to be compressed to a condition designated *a'''* in FIG. 13, and further rotation to condition *a''''* in FIG. 14, one of maximum compression. In this phase of the cycle, the first fuel charge has been compressed and forced through fuel outlet 102, tubing 103, into the valve assembly 110, where it is disposed to be injected into the chamber CB through the fire screen 112 upon the subsequent controlled and timed opening of the valve which occurs twice a cycle, each time momentarily after one of the vanes has swept clockwise past the fire screen 112. This is shown in FIG. 13, wherein it will be observed that the fuel charge, designated schematically *ar*, is being injected into a combustion sub-chamber temporarily formed behind the radially outer portion of the vane that has just passed the valve assembly 110, which portion extends radially beyond the ring means 46, and between a circumferential portion of the ring means and a portion of the surface 70. This is an extremely small space designated by CB' in FIG. 13 and may be considered a temporary detonation sub-chamber, which, it will be observed, is sealed along one axial side at line *x*. A moment later, the valve is closed automatically by the control and timing means and the spark plug is energized just after the vane passes it, and causes the fuel charge to explode, designated by *ae*, exerting a substantial force on the lower side of the vane, as shown in FIG. 14, which results in a strong reactive impulse on and clockwise motion of the vane. The driving reaction of the vane to the fuel detonation is the fundamental driving force produced by the engine, and it both forces the ring means 46 to rotate clockwise and imparts a direct rotative force on the shaft 40. While this vane has thus been rotating to form the temporary detonation sub-chamber CB' and to be forced by the explosion of the first fuel charge therein, the other vane has induced the second charge of gaseous fuel into the compression chamber. This second charge of fuel is compressed in the compression chamber CP and ultimately is forced through the fuel outlet 102 and tubing 103 into the valve assembly 110 so as to be poised therein for subsequent injection into a second detonation chamber temporarily formed by the radially outer portion of the other vane behind it and between a circumferential portion of the ring means 46 and surface 70 after the outer edge of the other vane has passed the line *x*. When the other vane passes the valve fire screen 112, the valve in assembly 110 is opened to admit the second charge of fuel into the second temporarily formed detonation chamber and then is closed; thereafter, when the other vane passes the spark plug 114, the latter is automatically en-

ergized to ignite and detonate the second fuel charge and to impart a clockwise force on the other vane. It will be understood by those skilled in the art that the configuration and disposition of the cam 122, the switch 120 and the cam follower 130 are empirically determinable in a known way so as to cause the valve to open twice a cycle and the spark plug to spark twice a cycle, momentarily after the valve is closed, to cause two detonations of fuel per cycle and to thereby impart a clockwise rotative impulse force on each of the vanes once a cycle. As one of the vanes is reacting to a detonation on its trailing side, its forward side is scavenging the waste or unspent gases of a prior detonation which are disposed in a temporary sub-chamber formed in the combustion chamber CB on its forward side and ejecting them out through the exhaust vents 166. The spent gases being scavenged are designated *as* in FIGS. 13 and 14 during the phase when they are trapped within this temporary sub-chamber combustion in chamber CB before the exhaust vents are placed into communication with this temporary sub-chamber by the vane passing over the exhaust vents (see FIG. 13), and thereafter are designated *as'* when they are free to pass to the atmosphere through the exhaust vents 166, which at that time have been placed into communication with the combustion chamber (FIG. 14). As the vane moves past vents 166, it sweeps all spent gases out.

It will, therefore, be understood that our rotary engine will operate, once it is started, by the unique cooperative operation of the ring means and driving vanes mounted within the engine housing in such a manner that the vanes cooperate to individually and sequentially form temporary sub-chambers in the compression chamber to induce a charge of fuel and then compress it and deliver it to the fuel control valve, which is operated to inject the fuel charge behind a vane, which at that time operates on the exterior of the ring means to form a temporary combustion sub-chamber, and to react to the detonation of the compressed fuel charge therein, which is ignited by the spark plug that is timed to spark momentarily after the fuel control valve closes, so as to have rotary movement imparted to the vane. The rotary movement of the vane results in rotation of the power take-off shaft, in the case of vane 52 directly to the shaft 40 as they are keyed to each other, and in the case of vane 54 indirectly to the take-off shaft, since it floats thereon, by being transmitted through the ring means to and through the other vane 52 and then directly to the take-off shaft. The overall operation is such that two charges of fuel are individually detonated each cycle. The timing and control means is designed so the induction of the fuel charges, their compression, transferral to the fuel control valve, injection into the temporary combustion sub-chamber, and detonation therein, are all operated in half-cycle sequences. Throughout, the flywheel operates to provide smooth operation.

Starting of our engine may be by rope cranking, as previously described, or starting can be accomplished by known automatic mechanical or electro-mechanical means or by injecting compressed air into the compression chamber. For the latter purpose, an auxiliary compressed air inlet may be formed and disposed adjacent the fuel inlet 100.

Starting may be facilitated, if desired, by injecting atomized water into the compression chamber before firing commences to help fill the volume therein. This desirable technique contributes to smooth engine operation and also possesses the attribute of cooling the engine; this technique cannot ordinarily be utilized in a piston-cylinder engine, because the atomized water would short out the spark plug. Regardless of the mode and means of starting employed, it should be noted that "kick back" during starting is not possible with our engine because of the unidirectional operation of the driving vanes.

Although the fitting and tubing means for the fuel sup-

ply system, both from the carburetor to the fuel inlet in the compression chamber, and from the fuel outlet in the compression chamber to the fuel control valve, have been illustrated as comprising separate fittings and tubes. It will be realized by those skilled in the art that appropriate passageways and/or channels may be conveniently formed in the engine housing and substituted therefor, if desired.

Although the ignition system has been described as being an ignition coil-battery-switch arrangement, if desired, the ignition coil, battery, switch and flywheel illustrated may be replaced by a flywheel magneto constructed to fire twice a cycle.

Although not illustrated, the engine may be conveniently and efficiently cooled by either the provision of cooling fins on the exterior of its housing or by mounting a water cooling jacket around its housing.

It should be noted that the fire screen 112 operates to prevent overheating of and flash-back into the fuel control valve.

The substantially frictionless operation of the engine should be noted. The engine includes a minimum of high friction points and much of the contact between the parts is low friction rolling contact. Sliding contact occurs between the driving vanes and the slippers; however, even this friction has been minimized to a maximum degree by the unique slippers which are mounted in the ring means to pivotally oscillate and to provide a snubbing bearing and sealing contact with the driving vanes which can be effectively lubricated by an oil mist that can be readily generated in the compression chamber by injecting oil therein in any convenient manner.

In view of the foregoing, it will be apparent that we have provided a rotary engine which satisfies the object of this invention. Our rotary engine is extremely simple in construction and includes few moving parts, most of which are in low friction rolling contact, hence wear on the engine parts is kept to a minimum; has an extremely low weight and size to horsepower ratio; may be operated on a variety of fuels, such as gasoline, kerosene or propane; most of its parts may be readily die-cast by a minimum number of dies; horsepower ratings of it may be varied, if desired, simply by filling in axial portions of dies to thereby vary the axial dimensions of the housing, hence, of the compression and combustion chambers and the driving vanes and ring means to be used; is readily adaptable to series mounting to increase horsepower without creating and difficult synchronizing problems; starting of it may be accomplished by compressed air and all possibility of kick-back during starting has been eliminated; it includes a simple and accurate timing arrangement which does not require the advancing or retarding of the spark during changes in r.p.m.; and a supercharger is inherently built into the engine. The foregoing are desirable features in an internal combustion engine and their achievement in our engine contributes to the satisfaction of the object of our invention.

In FIGS. 15-18 we have illustrated another form of the invention which is particularly well suited for power applications over ten horsepower, though not limited thereto. This form of the invention operates on the same general principle as the first form, namely, that of utilizing a cylindrical ring means to divide a cylindrical compartment into a compression chamber and a combustion chamber, a plurality of driving vanes extending through said ring means, and a take-off shaft associated with the ring means and driving vanes for joint rotation therewith relative to a housing, and utilizing the reactive forces on the vanes to explosions of fuel charges to cause such rotation. The principal difference between the two forms of the invention resides in the fact that in the second form, all of the force applied to the driving vanes is transmitted through the ring means to the power take-off shaft, as contrasted with the first form wherein the force

applied to one of the driving vanes (the one which is directly keyed to the take-off shaft) is transmitted directly to the take-off shaft. The fuel supply means, the ignition means and the timing and control means may all be the same in the second form as in the first form and the variations in these means set forth with regard to the first form may also be made in the second form. A specific variation which may be very successfully employed in the second form is that of utilizing a pressurized fuel injection, fuel supply system.

Therefore, there are many structural similarities in the two forms, the principal structural differences residing in the physical construction of the driving vanes, ring means, take-off shaft and engine housing to effect complete transmission of force from the driving vanes to the take-off shaft through the ring means. Structural elements in the two forms which may be common are, therefore, designated by the same reference numerals but with a prime (') added where they are employed in the second form. Structural elements which are constructed differently in the second form will have fresh reference numerals applied to them. The materials of which the parts are made correspond in the two forms.

The engine housing in the FIGS. 15-18 form of the invention generally comprises a main housing section 170 and a detachable end cap 172 which cooperate when assembled to form a solid cylindrical compartment C'. Mounted within the compartment C' is a ring means 174 which is eccentrically mounted relative to the compartment and which generally subdivides it into a compression chamber CP' circular in cross section, and a combustion chamber CB' generally crescent-shaped in cross section. The ring means 174 includes a cylindrical, side wall 176 and a diametral, flat, end wall 178. Extending coaxially through the ring means 174 is an elongated take-off shaft 180 having an integrally formed, radial flange 182 disposed contiguous with and rigidly secured to the ring means end wall 178, as by securing screws 184. The ring means and take-off shaft are, therefore, functionally a unit that is adapted to rotate jointly and uniformly. The ends of the shaft 180 extend in both axial directions completely through the housing where their free ends are accessible for power take-off.

The engine housing is designed to accommodate this ring means-shaft unit for rotation. For this purpose the inner surface 186 of the engine housing end wall 188, which is circular, generally flat and diametrically disposed to form one end wall of the compartment C', has an eccentric circular recess 190 and a coaxial, communicating, smaller circular recess 192 formed therein, which communicate with a coaxial bore 194 that extends completely through an axial projection formed on end wall 188. With particular reference to FIG. 17, it will be observed that the right-hand end of the take-off shaft 180 extends through the bore 194, being supported therein and sealed by a pair of radial antifriction bearing and sealing assemblies 196, and has its flange 182 disposed in the recess 192 and the ring means end wall 178 disposed in the recess 190. The free open end 198 of the ring means is disposed within the free open end 200 of the main housing section 170; however, it extends axially slightly beyond end 200 where it is positioned to be disposed in a circular groove 202 formed in the inner surface of the end cap 172 and be supported therein for rotation when the latter is attached to the main housing section. The take-off shaft 180 extends through a bore 204 formed eccentrically in the end cap 172 which is arranged to be disposed coaxially with the bore 194 when the end cap is attached to the main housing section. The end cap includes one or more radial antifriction bearing and sealing assemblies 206 for supporting and sealing the left-hand end of the take-off shaft (with reference to FIG. 17). Therefore, the ring means 174 is arranged to be supported for rotation jointly with the take-off shaft 180 by the engine housing in recesses 190 and 192, groove 202 and bores 194 and 204 formed in the engine housing components.

A pair of driving vanes 208, 209 are arranged to be rotatably mounted coaxially within the compartment C' and to extend radially therein. The driving vanes 208, 209 are similarly constructed and each includes a main flat driving portion and a mounting hub comprising a pair of axially spaced rings 210 and 211, respectively. The rings 210 and 211 are arranged to be disposed coaxially and to mesh to form a solid tubular hub and to be supported on cylindrically disposed antifriction bearings 212 that are, in turn, supported on an axially inwardly extending, cylindrical plug 214 formed integrally with the end cap 172. The driving vanes extend radially through a pair of slots 216 which are formed by vane bearing and sealing means that are diametrically disposed in axially extending openings formed in the cylindrical side wall 176 of the ring means. Bearing and sealing means 218 are constructed and disposed in the same general manner as the bearing and sealing means of the first form of the invention. To facilitate mounting of the driving vanes 208, 209, bearing and sealing means 218 and the ring means 174, the free end 193 of the ring means 174 may comprise a separate detachable end ring made of good bearing material, that may be detachably secured to the cylindrical side wall 176 of the ring means after the driving vanes and slippers that comprise the vane bearing and sealing means 218 have been axially slid into their receiving openings in the ring means side wall 176 which are open at the free end of the ring means when the separate end ring 193 is detached therefrom. Thereafter, the end ring 193 may be secured to the ring means side wall 176 to retain the driving vanes and slippers therein.

To assemble the second form of the invention, after the ring means, driving vanes and take-off shaft have been assembled, with reference to FIG. 17, the right-hand end of the take-off shaft may be inserted and pushed through the bearing and sealing assemblies 196 in main housing end wall 188, and the end cap 172 may then be slid over the left-hand end of the shaft 180, and adjusted until the driving vanes mounting rings 210, 211 slide onto the bearings 212 and the groove 202 in the end cap slides over the ring means end ring 193. In this connection it will be observed that the bore 204 in the end cap extends completely through plug 214, eccentrically relative thereto and that the bearing and sealing assembly 206 ultimately supports the shaft. At this time, the parts will be fully assembled and disposed as illustrated in FIG. 17, and the end cap 172 may be rigidly secured to the main housing section 170, as by tightening nuts 219 on the mounting bolts 220 which extend through appropriate openings 222 in the end cap and are anchored in threaded openings 224 formed in the free end 200 of the main housing section.

Because the ring means 174 includes integral, diametral, end wall 178, the fuel inlet from the carburetor 106' and the fuel outlet from the compression chamber CP' to the fuel control valve assembly 110' cannot be formed in the end wall 188 of the main housing section, as in the first form. However, these elements may be conveniently formed by appropriate passageways and openings formed in the end cap 172, and therefore, the fuel inlet 226 from the carburetor 106' is illustrated as formed in the end cap, as is the fuel outlet 228 from the compression chamber CP' to the fuel control valve assembly 110'. With reference to FIG. 18, the direction of rotation of the driving vanes 208, 209 is in the counterclockwise direction in operation, and the other elements of the engine are appropriately disposed as illustrated.

The operation of the second form of the invention is substantially the same as that of the first form, and therefore, will not be repeated at this point. The supply of compressed fuel to the fuel control valve assembly, injection into the combustion chamber, detonation of the compressed fuel and the control and timing of the opening and closing of the fuel control valve 110' and sparking of the spark plug 114', are all substantially the same

as in the first form. The principal functional difference is that the reactive force of the explosion of the fuel which occurs twice a cycle as in the first form, is applied totally indirectly to the take-off shaft 180 through the ring means 174, which is rigidly secured to the take-off shaft. The take-off shaft, ring means and driving vanes rotate jointly; however, neither of the driving vanes is directly connected to the driving shaft, hence during such rotation, both of the driving vanes oscillate individually in the end bearing and sealing means 218. The overall operation of the second form of the invention is somewhat better balanced and quieter than that of the first form, and therefore, adapts itself admirably to higher capacity applications of the engine.

It will, therefore, be apparent that the second form of the invention also satisfies the object of the invention.

As will be evident from the foregoing description, certain aspects of our invention are not limited to the particular details of construction of the examples illustrated, and we contemplate that various and other modifications and applications will occur to those skilled in the art. It is, therefore, our intention that the appended claims shall cover such modifications and applications as do not depart from the true spirit and scope of our invention.

We claim:

1. A rotary internal combustion engine comprising: a housing including wall means defining an internal cylindrical compartment having a cylindrical side wall and spaced flat parallel end walls; a cylindrical hub positioned within said compartment and extending coaxially therethrough, said hub consisting of a pair of rotatable cylindrical support rings; a cylindrical ring means of greater diameter than said hub, said ring means encircling said hub and mounted in said compartment for rotation relative to said housing about a fixed axis therethrough, said fixed axis coinciding with the axis of said ring means and being parallel to and eccentrically disposed relative to said compartment axis, said ring means having line sealing and bearing engagement with said housing at said side wall along the line of intersection of a plane through both said axes with said side wall, and said ring means having line sealing and bearing engagement with said hub along the line of intersection of said plane with said hub, said ring means and said housing thereby cooperating to define a first compression chamber within said ring means and between the end walls of said compartment and the cylindrical surface of said hub and a second combustion chamber between said ring means and said side wall and the end walls of said compartment; an elongated power take-off shaft extending through said housing within said ring means; bearing means in said housing supporting said shaft for rotation; a pair of separate flat axially and radially extending driving vanes one vane attached to each of said support rings, said vanes and support rings disposed for rotation about said compartment axis, said driving vanes being disposed about said shaft in operative driving relationship thereto, said driving vanes extending from said hub through a pair of diametrically opposed spaced axially extending slots formed in said ring means and having their radially outer edges in a close sliding clearance fit with said housing at said side wall, said driving vanes having axially spaced parallel radially extending side edges in a close sliding clearance fit with the portions of said housing which define the end walls of said compartment, all of said shaft, said driving vanes and said ring means being jointly rotatable relative to said housing; inlet and outlet ports for said compression chamber in one of said compartment end walls, said ports being disposed on opposite sides of and closely adjacent to, the sealing engagement between said ring means and said hub, the inlet port being displaced from said sealing engagement in the direction of said ring means rotation; inlet and outlet means for said combustion chamber disposed in the cylindrical side wall of said compartment, said inlet and out-

let means being disposed on opposite sides of, and adjacent to, the sealing engagement between said ring means and said housing, said outlet means comprising a plurality of slots through said compartment side wall and extending from a point closely adjacent said sealing engagement a substantial angular extent in a direction opposite the direction of said ring means rotation, said inlet means comprising inlet chamber means in said cylindrical side wall and extending radially outward from the inner surface of said side wall, a fire screen dividing said inlet chamber means from said combustion chamber; a port in the radially outer portion of said inlet chamber means, and fuel control valve means separating said fire screen from said port; conduit means interconnecting said inlet chamber means port and said compression chamber outlet port; means for supplying a gaseous or liquid fuel to the inlet port for said compression chamber; ignition means adjacent said inlet chamber means and arranged to periodically ignite fuel in said combustion chamber; means for timing and controlling the operation of said valve means and said ignition means in response to rotation of said shaft so as to periodically permit flow through said conduit means and said inlet chamber means and into said combustion chamber means and ignite it shortly thereafter.

2. An engine as defined in claim 1 wherein said driving vanes operate when rotated to cause fuel to be admitted into said compression chamber and be compressed therein, and said timing and control means operates in response to rotation of said driving vanes and said shaft to open said valve means and inject a charge of pressurized fuel from said compression chamber into said combustion chamber behind a driving vane relative to the direction of rotation thereof and to actuate said ignition means to ignite the pressurized fuel and cause it to explode and exert a force behind the driving vane, whereby there is an explosion of a charge of fuel for each driving vane and two explosions for each rotation of said ring means and shaft.

3. An engine as defined in claim 1 wherein each of said slots is formed by separate bearing and sealing means that is supported by said ring means for oscillation relative to a driving vane and is configured to closely embrace said driving vanes in substantially frictionless bearing and sealing relationship therewith.

4. An engine as defined in claim 3 wherein each of said bearing and sealing means comprises a pair of elongated slippers that are configured to cooperate when assembled to form a substantially elongated cylindrical portion with an elongated slot of a cross section to accommodate a driving vane.

5. An engine as defined in claim 1 wherein said housing includes a detachable end cap which defines one of the end walls of the compartment and includes a ring means mounting groove.

6. An engine as defined in claim 1 wherein said ring means comprises a cylindrical portion and an integral diametral end wall that is rigidly secured to said drive shaft; and said drive shaft is coaxial with said ring means.

7. An engine as defined in claim 6 wherein said driving vanes are mounted for rotation on a supporting plug formed on said housing and extending coaxially through said compartment, and a bore is formed eccentrically through said plug and arranged to receive and support said drive shaft.

8. An engine as defined in claim 7 wherein said vanes include spaced tubular mounting rings which mesh when mounted on said plug to form a continuous tubular hub.

9. An engine as defined in claim 6 wherein at one of said end walls said housing includes a circular recess for receiving said ring means end wall, and at the other of said end walls a groove is formed coaxial with said recess to receive the end of said ring means opposite to the end wall thereof.

10. A rotary internal combustion engine comprising: a housing including wall means defining an internal cylindrical compartment having a cylindrical sidewall and flat spaced first and second parallel end walls; said first and second end walls defining, respectively, first and second aligned circular grooves; a cylindrical ring means of smaller diameter than and mounted within said compartment for rotary movement relative to said housing, said ring means comprising a pair of substantially semi-cylindrical sections and a pair of end rings detachably secured to the axial end edges of said sections forming the opposite ends of said ring means; said opposite ends being positioned for rotation in the aligned first and second grooves of said first and second end walls in sealing and bearing relationship therewith; said ring means and said compartment having their axes spaced and parallel; said ring means being eccentrically disposed relative to said compartment and having an axially extending side portion thereof in line sealing and bearing engagement with said housing at said side wall, said ring means and said housing thereby cooperating to define two chambers within said compartment, a compression chamber within said ring means between the end walls of said compartment and a combustion chamber between said ring means and said side wall and the end walls of said compartment; an elongated power take-off shaft extending through said housing and being disposed coaxially with said compartment within said compression chamber; said housing having bearing means for supporting said shaft for rotation; a pair of separate flat axially and radially extending driving vanes disposed in said compartment; one of said driving vanes being rigidly connected to said shaft, extending radially through said ring means and having its radially outer edge in a close sliding clearance fit with said housing at said side wall; the other of said driving vanes being mounted on said shaft for relative rotation thereto, extending radially through said ring means and having its radially outer edge in a close sliding clearance fit with said housing at said side wall; said ring means including a pair of diametrically opposite spaced axially extending slots through which said driving vanes extend; said driving vanes having spaced parallel radially extending side edges in a close sliding clearance fit with the portions of said housing which define the end walls of said compartment; whereby said shaft, said driving vanes, and said ring means are arranged for joint rotation relative to said housing; means for supplying a gaseous or liquid fuel to the interior of said compression chamber; fuel control valve means for controlling injection of fuel under pressure into said combustion chamber; means connecting the interior of said compression chamber with said valve means; ignition means for igniting fuel in said combustion chamber; means for timing and controlling the operation of said valve means and said ignition means so as to inject fuel under pressure and ignite it shortly thereafter; and means for scavenging said combustion chamber.

11. An engine as defined in claim 10 wherein said sections have spaced opposed axially extending side edges which cooperate to define a pair of diametrically opposite spaced axially extending spaces; and separate bearing and sealing means are disposed in said spaces and supported by said ring means; said bearing and sealing means being mounted for oscillation and being configured to form said slots and to closely embrace said driving vanes in substantially frictionless bearing and sealing relationship therewith.

12. An engine as defined in claim 11 wherein each of said bearing and sealing means comprises a pair of elongated slippers that are configured to cooperate when assembled to form an elongated substantially cylindrical portion of a length equal to the axial length of said sections, an elongated slot of a cross section to accommodate one of said driving vanes, and a pair of oppositely axially extending mounting axle portions; and said end

rings include bearing sockets for receiving said axle portions.

UNITED STATES PATENT OFFICE
CERTIFICATE OF CORRECTION

Patent No. 3,194,220

July 13, 196

James M. Dowell et al.

It is hereby certified that error appears in the above numbered patent requiring correction and that the said Letters Patent should read as corrected below.

Column 4, line 55, before "driving" insert a hyphen; same line 55, before "ring" insert a hyphen; column 9, line after "housing" insert a period; line 48, for "and" read -- any --; column 12, line 32, after "means" insert -- of smaller diameter than said compartment --.

Signed and sealed this 28th day of December 1965.
